UNITED STATES PATENT OFFICE.

SAMUEL GREENEBAUM, OF KANSAS CITY, MISSOURI.

TILE OR ANALOGOUS SIMULATION.

Application filed November 29, 1926. Serial No. 151,541.

The invention is a new and improved wall or ceiling covering in the nature of a tile or other simulation, which may be manufactured in numerous finishes to represent 5 enameled tile, ceramic tile, unglazed tile, enameled or unglazed brick, marble, stone, terra cotta, mosaic, etc.

The principal objects of the invention are to provide a covering which may either be 10 used in new construction or may be applied over existing walls, ceilings or other work; to make novel provision whereby grooves which outline the tile or other simulations, may be pointed up with plaster of Paris, 15 Keene cement, Portland cement, or any other cement or plastic material suitable for the purpose, thus giving an excellent representation of tile work and mortar joints; to provide a tile simulation which may be made 20 either rigid or flexible, according to the use to which it is to be put, the flexible feature making the product adaptable for use around columns, curved surfaces, rounded corners, etc.; to provide such a simulation 25 with a rear side having a texture permitting the use of cement for securing such simulation against a flat surface, so that after hardening of the cement, there is no danger of any loosening or puckering; to provide a 30 simulation in sheet form and of such nature that it may readily be cut by hand and fitted at the place where it is to be used, into desired sizes and shapes; to provide a simulation which need not be over one-eighth or 35 three-sixteenth of an inch in thickness, making it possible to apply the covering on existing work, without encroaching too much upon the existing trim or woodwork, and to provide a tile simulation which, while rather 40 simple and inexpensive, and easy to manufacture and apply, will be durable, artistic and in every way desirable.

With the foregoing in view, the invention resides in the novel subject matter herein- 45 after described and claimed, the description being supplemented by the accompanying drawings.

Fig. 1 is a small front elevation of a portion of a tile simulation constructed in accordance with the invention, said simulation being in the form in which it is placed on sale, that is, with the grooves empty.

Fig. 2 is an enlarged fragmentary front elevation of a portion of the simulation in 50 the same state as shown in Fig. 1.

Fig. 3 is a detail sectional view on line 3—3 of Fig. 2.

Fig. 4 is a fragmentary elevation of a portion of the simulation used as wainscoting and illustrating it in connection 60 with a wainscoat cap, the grooves in the simulation when installed, being filled with pointing material, as indicated in this view.

Fig. 5 is a detail section on line 5—5 of 65 Fig. 4.

In constructing the invention, I make use of a sheet 6 of any desired material or materials and proportions, but preferably of a thickness varying from one-eighth to three-sixteenths of an inch, according to the use 70 for which the simulation is designed. For this sheet, rubber, asbestos and cement, asbestos and magnesia, compositions such as "linoleum" or other desired materials, may 75 be used.

The sheet is intended to be secured in place by suitable viscous cement and to insure that the cement shall properly adhere to the sheet, I provide the rear side of this sheet with a texture to which the cement 80 will readily stick. This may well be accomplished by embedding closely woven fibrous fabric in the rear portion of the sheet with all or some of the woof and warp exposed 85 at the rear surface. Such fabric is indicated at 7 in Figs. 3 and 5 and when "linoleum" is used in the manufacture of the invention, this fabric is of course an integral part of the "linoleum" sheet as purchased from the 90 factory, to be used for the production of the present invention. If other materials are to be used, a sheet of the fabric 7 may be covered with a layer of any desired plastic material which, when hardened, will 95 possess the desired characteristics. This material of course permeates into the weave of the fabric 7 so that a unitary sheet is produced, having a fabric-impregnated rear side.

In the front side of the sheet 6, I form a 100 plurality of angularly or otherwise related grooves 8, and the portions 9 of said front, between the grooves, are finished (by coating or in any other suitable way) to simulate tile. This finishing is accomplished in the 105 present disclosure, by coating the sheet 6 with lacquer, enamel, paint, varnish or the like and this coating may or may not extend over the surfaces of the grooves 8, as desired. Such a coating is illustrated at 10 in Figs. 3 110

and 5, and it will be understood that when such a coating is used, it may be sprayed on or otherwise applied in shades or combinations of shades, or stippled, or mottled, etc., so as to produce tile effects of infinite varieties.

After the tile simulation is cemented in place and held until the cement has set, the grooves 8 are filled with any desired plastic, pointing material, such as those hereinbefore enumerated. Thus, the appearance is given of an excellent grade of tile, well laid and secured by mortar joints. An idea of the appearance of the finished work, is given in Fig. 4. In this view, the simulation has been used for wainscoating, and a wainscoat cap 12 is shown in connection with it. Such a cap, base finishes, trim, etc., may be provided, constructed in a fashion similar to the tile simulation herein described. In Figs. 4 and 5, the pointing material, simulating mortar joints, is denoted at 11.

By making use of the construction herein disclosed, or an equivalent construction, a product is provided possessing great commercial merit, and on account of the advantages existing from the details herein disclosed, they are preferably followed. However, within the scope of the invention as claimed, variations may be made and it will be understood that I am not restricted to the size or shape either of the sheet 6 or the tiles simulated. Moreover, the surfaces of the tile simulations 9 may be finished in any desired manner, during any desired part of the manufacturing process, and it is to be understood that the word "tile" is herein used for convenience rather than in a limiting sense, as numerous other formations could well be simulated with the invention.

The grooves may be made by groove cutters where the tile or other design is simple, or in either simple or intricate designs and patterns, grooving may be accomplished by stamping or indenting the sheet under pressure before hardening of the material of which it is formed, takes place, or by the so-called stencilling process.

In the application of this invention, the sheets 6, or other shapes, are cemented in

positions adjacent to each other, leaving a space between them the same size as the groove. This space is pointed up at the same time and with the same material as used in the grooves, thereby completely concealing the junction of the plurality of sheets, units or shapes used, and rendering the entire surface in one uniform treatment.

There may be some instances where in the practical application of this material to the wall or ceiling, it will be found necessary to nail the material through the grooves to the wall or ceiling to keep the material in place until the cement has set up. If this is done, the nails or brads would be driven to the bottoms of the grooves and the pointing material applied in the usual manner, concealing the nails.

I claim:

1. A wall covering comprising a sheet of pliable nature throughout its thickness, the front side of said sheet being provided with open receiving and retaining grooves for a plastic pointing material, and with a plurality of independent areas bounded by said grooves, said areas being finished to represent tiles.

2. A wall covering comprising a rectangular sheet of pliable nature throughout its thickness, the front side of said sheet being provided with open receiving and retaining grooves for a plastic pointing material, said grooves being straight from edge to edge of the sheet and bounding a plurality of independent areas, said areas being finished to represent tiles.

3. A wall covering comprising a sheet of pliable nature throughout its thickness and embodying a fabric backing, the front side of said sheet being provided with open receiving and retaining grooves for a plastic pointing material, and with a plurality of independent areas bounded by said grooves and finished to represent tiles, said grooves being of a depth extending substantially to said fabric backing.

In testimony whereof I have hereunto affixed my signature.

SAMUEL GREENEBAUM.
